Patented Apr. 8, 1975

234,755

BOB SLED

Andrew Carlyle Bogdanovich, 1691 Edgewater Lane,
Camarillo, Calif. 93010

Filed Feb. 4, 1974, Ser. No. 439,052

Term of patent 14 years

Int. Cl. D12—14

U.S. Cl. D12—10

FIG. 1

FIG. 2

FIG. 5

FIG. 6

FIG. 3

FIG. 4

FIG. 1 is a perspective view of a bob sled showing my new design;

FIG. 2 is a side elevational view thereof;

FIG. 3 is a top plan view thereof;

FIG. 4 is a bottom plan view thereof;

FIG. 5 is a front elevational view thereof; and

FIG. 6 is a rear elevational view thereof.

I claim:

The ornamental design for a bob sled, substantially as shown.
